EGG-SHAPED CONTAINER FOR FOOD OR THE LIKE

James D. Smith, South Buffalo Township, Armstrong County, Pa., assignor to Aluminum Company of America, Pittsburgh, Pa., a corporation of Pennsylvania

Filed Oct. 8, 1969, Ser. No. 19,469

Term of patent 14 years

Int. Cl. D9—04

U.S. Cl. D9—219

FIG. 1.

FIG. 2.

FIG. 3.

FIG. 1 is a top plan view of an egg-shaped container for food or the like.

FIG. 2 is an elevational view thereof.

FIG. 3 is a cross-sectional view thereof taken along line III-III of FIG. 1.

I claim:

The ornamental design for an egg-shaped container for food or the like, substantially as shown.
